UNITED STATES PATENT OFFICE.

BENJAMIN F. KEENEY, OF WATERTOWN, SOUTH DAKOTA, ASSIGNOR OF ONE-HALF TO ANTHONY L. SHORE, OF MINNEAPOLIS, MINNESOTA.

BOILER WASHOUT DEVICE.

SPECIFICATION forming part of Letters Patent No. 655,559, dated August 7, 1900.

Application filed March 16, 1900. Serial No. 8,893. (No model.)

To all whom it may concern:

Be it known that I, BENJAMIN F. KEENEY, a citizen of the United States, residing at Watertown, in the county of Codington and State 5 of South Dakota, have invented certain new and useful Improvements in Boiler Washout Devices; and I do hereby declare the following to be a full, clear, and exact description of the invention, such as will enable others 10 skilled in the art to which it appertains to make and use the same.

My invention has for its object to provide an improved device for washing out sediment from liquid-containing receptacles, and is 15 especially designed for use in connection with steam-boilers to remove the sediment deposited therein from the water.

To the above ends the invention consists of the novel devices and combinations of devices 20 hereinafter described, and defined in the claims.

The invention is illustrated in the accompanying drawings, wherein like characters indicate like parts throughout the several 25 views.

Figure 1 is a view in side elevation with some parts broken away, showing the boiler and fire-box of a locomotive or other portable engine, the same having applied thereto one 30 of my improved washout devices. Fig. 2 is a plan view with some parts sectioned and others shown in diagram of the washout device shown in Fig. 1. Fig. 3 is an enlarged view in vertical section on the line $x^3 x^3$ of 35 Fig. 2. Fig. 4 is a transverse section on the line $x^4 x^4$ of Fig. 3. Fig. 5 is a transverse section on the line $x^5 x^5$ of Fig. 1. Fig. 6 is a plan view showing a modified form of the washout device. Fig. 7 is a view in side elevation with some parts broken away, showing the parts illustrated in Fig. 6. Fig. 8 shows 40 a boiler in end elevation with some parts broken away and others removed and illustrating the washout device as applied within a catch-trough which is suspended below the flues; and Fig. 9 is a detail view in side elevation, showing the inner end section and scraper of the washout-tube employed with the construction illustrated in Fig. 8.

50 The numeral 1 indicates the body of the boiler, and the numeral 2 the fire-box, of a lo-

comotive or portable engine such as found in general use. In the preferred arrangement I apply one of my improved washout devices on each side of the fire-box 2, at the 55 bottom of the water-leg formed between the said fire-box and the adjacent portion of the boiler. It is at the bottoms of the these water-leg portions that the sediment accumulates in quantities, and to remove such sediment the boilers are usually provided with several hand-holes that are normally closed by hand-hole covers 3, held by the bolt and bracket 4 5, or otherwise. The sediment is deposited in a heavy pasty mass, and it has 60 been found difficult to wash the same from the boiler by a flushing action. By my invention I readily remove the sediment by the use of a discharge-tube which projects into the boiler in the vicinity of the sediment and 65 is provided with one or more inlet-openings, together with means for shifting the point of opening into the tube over different points in the vicinity of the sediment, so that the out-flowing current of water, which of course carries the sediment with it, will be caused to 70 continually change its course or to flow from different points. The tube is also provided with agitating blades or flanges for stirring up the packed sediment, so that it will be 75 more readily carried by the water.

The invention in its preferred form is illustrated in Figs. 1 to 3, inclusive, wherein the outlet-tube is made up of two telescoped tubular sections or members *a* and *b*. The 85 outer tube *a* extends along the bottom of the water-leg formed at the side of the fire-box 2, and its forward end projects through and works in a stuffing-box 6, applied to the forward lower portion of the water-leg section 90 of the boiler. Said tube *a* is thus mounted with freedom for a rotary movement and also with freedom for a limited longitudinal movement, its outward movement being limited by a collar *a'* on the said member *a*. At its 95 outer end the tubular member *a* is provided with a stuffing-box *a''*, through which the outer end of the interior member or tube *b* projects. Just inward of the stuffing-box *a''* the member *a* is provided with a projecting 100 disk or flange *a''''*, with which the downturned end of a spring-keeper *c*, secured on the

boiler, normally engages to hold the tubular member a in the longitudinal position. (Indicated in Fig. 1.) At its extreme outer end the inner member or tube b is formed with a head b' and with a hand-wheel b^2 . The head b' has a spiral cam-flange b^3 , which extends in a plane perpendicular to its axis, except at the cam-sections b^4 , where the flange or thread advances abruptly. Secured on the disk or flange a^3 of the outer tube or member a is a forwardly-projecting bracket a^4 , provided at its outer end with depending fingers or lugs a^5 , that embrace the cam-flange b^3 of the head b' . For a purpose which will hereinafter appear the bracket a^4 is preferably provided with a pointer or finger a^6 , which cooperates with markings b^5 on the peripheral portion of the hand-wheel b^2 . From the outer end of the tubular member b a pipe f extends to some suitable point of exhaust, and this pipe is preferably provided with a stop-cock f' for opening and closing the same. Within the boiler the inner tubular member b is provided with a plurality of perforations or inlet-passages b^6 b^7 , which in the construction illustrated are located on a line extending parallel to the axis of the said tube. The outer tube a is provided with a series of perforations or inlet-openings a^7 and a^8 , that extend on a line running spirally around the said tube a . The said perforations a^7 a^8 extend in a circumferential direction, each ninety degrees in advance of the other, and the perforations a^7 and b^6 are equally spaced apart and normally stand longitudinally in line with each other. The perforations b^7 and the perforations a^8 are also equally spaced, but stand normally out of longitudinal line with each other. This relative arrangement of the perforations is best indicated in Fig. 2, wherein the outer tube a is shown as if split and laid out flat. With this construction as the outer tube a is rotated step by step one-quarter turn at each step the perforations b^6 and a^7 will be successively brought into registration from the inner end of the tube toward the forward end of the same, and the perforations b^7 and a^8 being set longitudinally out of line with each other will all be kept closed. It is evident that only a limited number of the perforations a^7 can be opened in succession without causing two or more of the same to be opened at one time. Hence it is that the shifting device, as shown in the form of the cam-flange b^3 , is employed. This cam-flange by the next movement after the last perforation a^7 has been opened, acting on the bracket a^4 , moves the outer tube a longitudinally far enough to bring the perforations b^7 and a^8 into longitudinal line with each other, and this same movement moves the perforations a^7 and b^6 out of longitudinal line with each other. Hence under the succeeding steps of movement of the tube a in the direction indicated by the arrow marked on Fig. 4 the perforations b^7 and a^8 will be brought into registration in succession, while the perforations

a^7 and b^6 will be held closed under all rotary positions of the said tube. In the construction illustrated the tube a is given but two longitudinal adjustments under the action of the cam-flange b^3 ; but it will of course be understood that the above principle of construction may be carried out to any desired extent. Of course the reverse rotation of the outer tube a will bring into registration the co-operating perforations of the two tubes in reverse order. It will also be understood that the construction may be reversed by mounting the inner instead of the outer tube for rotary movement and providing the same with the spirally-arranged series of perforations. The two tubes may together be given a slight longitudinal movement through the stuffing-box b , but for this purpose the discharge-pipe f should either be flexible or provided with a flexible joint. On the exterior of the tube a is a spirally-arranged series of **U**-shaped flanges a^9 , that embrace one each of the perforations a^7 a^8 . When the two tubes are moved together longitudinally or when the outer tube a is rotated, these flanges a^9 stir up the pasty sediment, so that it will be taken up by the water, and the said flanges further serve to direct the flow of the water to the particular perforation which happens to be open.

The modification illustrated in Figs. 6 and 7 comprises a single tube or pipe g , which would be used in lieu of the compound tube above described. This tube is open at its inner end and is provided thereat with a **U**-shaped scraper or agitating-flange g' , which projects rearward of the said open end. The tube g may or may not have a rotary movement, but it must have a long longitudinal movement through the gland or bearing g^2 , in which it works. At its outer end said tube g is provided with a stop-cock g^3 for opening and closing the same, and from its extreme outer end a flexible tube or hose would usually be extended to a suitable point of discharge. With this form of washout-tube the said tube is moved longitudinally, while the valve g^3 is open to clear the boiler of the sediment, and the scraper g' will under such movements stir up the sediment, so that it will be readily carried by the water which runs into the said tube. By moving the tube endwise the open inner end of the same is moved over different points in the vicinity of the sediment, so that the sediment will all be washed from the boiler. The pressure from within the boiler will tend to force the tube g outward; but it will require considerable force to move the said tube inward against such pressure. Hence I preferably employ a windlass, such as shown in Figs. 6 and 7, for forcing the tube inward. This windlass, as shown, comprises a windlass-shaft g^4 , mounted in suitable bearings g^5 on the bearing g^2 and provided with a pair of sheaves g^6 and a crank g^7 . The sheaves g^6 are connected by cords g^8 to a transverse bar g^9 , secured to the

outer end of the tube g . To lock the tube g in its innermost position, it is provided with a pin g^{10} , which by a slight rotation of said tube may be engaged or disengaged with a latch g^{11} on the bearing g^2 .

The construction illustrated in Figs. 8 and 9 is that which would usually be employed in stationary boilers of cylindrical form with horizontally-disposed tubes. The numeral 7 indicates such a boiler, having the tubes 8 and, as shown, provided at one end with a manhole 9, which in Fig. 8 is shown as opened. In this construction I suspend by means of suitable hangers k , engageable at their upper ends with certain of the tubes 8, a long catch-trough k' , which underlies the lower and central tubes. Under the boiling action within the boiler the sediment will be carried upward from the bottom of the boiler and will be deposited within the trough k' . Hence the washout-tube is in this case applied at the bottom of the said trough k' . The washout-tube which is shown as applied to this trough k' corresponds to the washout-tubes g illustrated in Figs. 6 and 7, the only variation being in the form of the agitator or scraper carried at the inner open end of the said tube, which in this construction instead of being U-shaped is of triangular form, as indicated at g^{12} , and is supported from the tube by a strap g^{13} .

The washout devices above described are intended to be applied to the boilers as permanent parts thereof, which may be used whenever necessary or desirable to clear the boiler of sediment.

The construction illustrated in Figs. 1 to 5, inclusive, has the advantage over the other construction that it may be applied to locomotive-boilers and boilers of other construction, many of which have valve-gear mechanism and other devices which would prevent the washout-tube from being given such an extended longitudinal movement as is required to operate the washout device illustrated in Figs. 6 and 7.

From the foregoing description it is evident that my invention is capable of a large range of modification. It will also be understood that the washout device will be serviceable for cleaning out sediment for various other liquid-containing receptacles and hence that I desire to claim the device for any use to which it may be put.

The word "boiler" is used in the claims in a generic sense and is intended to include all liquid-containing receptacles.

What I claim, and desire to secure by Letters Patent of the United States, is as follows:

1. A boiler washout device, comprising a tube projecting into the boiler and provided with one or more inlet-openings, an agitating-blade in the vicinity of each opening, and means for shifting to different points within the boiler the opening into the said tube, substantially as described.

2. A boiler washout device, comprising a discharge-tube projecting into the boiler and provided with one or more inlet-openings, each opening having an agitating-flange in its vicinity, and the said tube having a movement within the boiler to agitate the sediment and vary the point of opening into said tube, substantially as described.

3. A boiler washout device, comprising a pair of telescoped tubes having longitudinally-spaced perforations adapted to be successively brought into registration by rotation of one of said tubes, substantially as described.

4. A boiler washout device, comprising a pair of telescoped tubes having longitudinally-spaced perforations adapted to be successively brought into registration by rotation of one of said tubes, and agitating-flanges in the vicinity of the openings in the outer tube, substantially as described.

5. A boiler washout device, comprising a pair of telescoped tubes having longitudinally-alined perforations adapted to be brought successively into registration by rotation of one of said tubes, and having other perforations adapted to be longitudinally alined by a slight longitudinal movement of one of the said tubes and then to be brought successively into registration by rotation of one of the said tubes, substantially as described.

6. A boiler washout device, comprising a pair of telescoped tubes having longitudinally-alined perforations adapted to be brought successively into registration by rotation of one of said tubes, and having other perforations adapted to be longitudinally alined by a slight longitudinal movement of one of said tubes and then to be successively brought into registration by rotation of one of said tubes, and a cam-flange carried by one of said tubes and acting upon the other tube to produce the said longitudinal movement, substantially as described.

7. A boiler washout device, comprising the tubes a and b rotatable one upon the other, said tube a having the perforations a^7 and a^8 and said tube b having the perforations b^6 and b^7 , disposed and operating as described, the cam-flange b^3 b^4 on said tube b , and the projection a^4 a^5 carried by said tube a , substantially as described.

8. A boiler washout device, comprising the telescoped perforations a and b , having perforations adapted to be registered by rotation of said tube a , and the U-shaped flanges a^9 embracing the perforations in said outer tube a , substantially as described.

In testimony whereof I affix my signature in presence of two witnesses.

BENJAMIN F. KEENEY.
